TO HEMPHILL COMPANY, OF CENTRAL FALLS, RHODE ISLAND, A CORPORATION OF
MASSACHUSETTS

METHOD OF PRODUCING KNITTED FABRICS HAVING LAP STRIPES AND YARN
VARIATION AND THE RESULTING FABRIC

Original application filed November 16, 1927, Serial No. 233,637. Divided and this application filed
January 3, 1928. Serial No. 244,072.

This application is a division of our co-pending application Serial No. 233,637, now Patent No. 1,702,608, dated February 19, 1929.

5 This invention relates to processes for producing knitted fabrics, particularly hosiery, and more especially seamless hosiery having lengthwise stripes made by additional threads, and also having patterning effects produced through yarn manipulation or variation, and more particularly through the manipulation of a plurality of yarns to produce plating and reverse plating, and also to the resulting fabric.

15 In order that the principle of the invention may be readily understood, we have disclosed two embodiments of the fabric of our invention and such portions of the mechanism for producing the same as are necessary to disclose the preferred method for producing the fabric.

In the drawings:

Fig. 1 is a side elevation of a seamless stocking having the lengthwise extending stripes which, for convenience of description, we shall herein refer to as reinforced or lap stripes, and also indicating the normal plating and reverse plating areas;

20 Fig. 2 is a plan view upon a greatly enlarged scale of the outside of a portion of the fabric shown in Fig. 1, and particularly representing the manner in which each additional thread is laid or incorporated in forming the reinforced or lap stripe;

35 Fig. 3 is a similar view looking at the fabric from the inner side;

Fig. 4 is a view generally similar to Fig. 1, and also representing the patterning effect produced by plating and reverse plating 40 of the main threads;

Fig. 5 is a view, somewhat similar to Fig. 2, of the outside of the stocking shown in Fig. 4, and particularly disclosing how the two main threads are positioned in the 45 plating and reverse plating;

Fig. 6 is a view similar to Fig. 5 but taken from the inside of the stocking or other fabric;

Fig. 7 is a plan view of the latch ring and 50 closely related parts of a circular knitting

machine, indicating the relation of the needle circle of the member or part whereby the additional threads are introduced to the needles;

55 Fig. 8 is a detail in side elevation of developments representing a portion of the circle of needles and the latch ring and yarn guides and the taking of an additional thread and the two main yarns by the needles in accordance with our invention; and

60 Fig. 9 is a detail showing a needle in side elevation and the means for feeding the additional thread thereto.

65 In accordance with our invention, we introduce one or more additional threads or 70 yarns to make longitudinal stripes spaced as desired, and which we herein refer to as reinforced or lap stripes. In the disclosed embodiment of the invention, we have represented the introduction of eight such additional threads, but it is to be understood that 75 the number may be varied as desired within the scope of our invention and that the introduction of said threads, or any of them, may be interrupted at predetermined points, 80 and particularly at the commencement of the heel and again at the commencement of the toe. The said additional threads are introduced through a special feeding device to which said threads are delivered from an 85 elevated bobbin carrier, stand or support, here shown as eccentrically arranged with respect to the needle cylinder.

85 The regular threads or yarns, which merely for purposes of distinction we will refer to as the main yarns, are at least two in number, and they are fed in a plating relation, as, for example, in the manner shown in the 90 patents to Robert H. Lawson, Reissue No. 16,584, April 5, 1927, and No. 1,605,896, November 2, 1926.

95 In accordance with our invention, the two main yarns are fed in any suitable manner in a normal plating relation, as hereinafter described in detail, and at desired times the plating is reversed so as to produce figures or patterns of any desired character between the lengthwise extending stripes produced by the said additional threads. So far as we are aware, we are the first, in a knitted 100

fabric, to provide lengthwise extending stripes or areas consisting of an additional thread for each stripe and two yarns fed in a plating relation, onto which the said additional thread or threads are superimposed, and desire to claim the same broadly.

In the disclosed embodiment of the invention, the said two main yarns are fed in a normal plating relation, and the additional threads by which the stripes are made upon the main yarns are received by the predetermined needles, so that at each point where the stripes are formed, three threads are received by the needles and knitted or incorporated thereby into the fabric, namely, the two plating yarns of threads and the said additional thread. The said two main yarns at the said stripe are laid and knitted in a normal plating relation with the said additional thread also knitted into the needles and appearing on the outer face of the fabric as a stripe covering the plating yarns and superimposed thereon. Between the said stripes the two main yarns alone are introduced, and they are knitted either in a normal plating relation or in a reverse plating relation, according to the dictates of the pattern mechanism. Even though two of the lengthwise stripes may be very close together, as shown for example in Figs. 3 to 6, the wales between said stripes may consist partly of normal plating and partly of reverse plating, or either, and the patterns in those parts of the fabric where the stripes are more widely separated may be varied as desired. While the normal plating and reverse plating operations are carried out in a manner broadly similar to the disclosure in the said patents to Lawson, and while the reverse plating may be effected in any suitable manner, we provide patterning mechanism disclosed in the parent application, and to which it is not necessary particularly to refer.

In Figs. 1 to 6 inclusive, we have represented two fabrics illustrative of the many that may be formed in accordance with our invention, and which may be taken as representative of the many different ones embodying the invention, and which may be formed by the mechanism herein disclosed. In the disclosed fabrics, we have represented hosiery, here shown as socks. In each of them there are represented the so-called lap stripes to which we have referred, and also normal plating areas and reverse plating areas between said lap stripes, it being understood that each lap stripe is, in the disclosed embodiment of the invention, superimposed upon a normal plating area. The reverse plating areas are, in the disclosed embodiment of the fabric of our invention, between the lap stripes. In the event that two of the lap stripes are relatively close to each other, as we will disclose in connec-

tion with Figs. 4, 5 and 6, the few wales between the closely adjacent stripes are herein partly formed in normal plating and partly in reverse plating. Referring more particularly to Figs. 1, 2 and 3, the nose is represented at 1. It is here shown as provided with a rib top 2 desirably incorporated with the rest of the stocking by a transferring process. The heel 3 and the toe 4 are both formed by a narrowing and widening operation. The dark lengthwise extending lines 5, 6, 7, 8, 9 are lap stripes formed as already stated. Between the lap stripes, the white areas (indicated generally at 10) are normal plating and the darker areas (indicated generally at 11) are reverse plating.

In Fig. 2, we have represented the outside of a portion of the fabric upon a greatly enlarged scale and have therein shown a portion of one of the lap stripes, as, for example, a portion of the lap stripe 7. The two main yarns, which are the yarns fed in a plating relation, are shown at 12, 13. An additional thread, which is introduced to form a lap stripe, is indicated at 14. The course of said lap thread, both at the inside and at the outside of the fabric, is indicated in the two views Figs. 2 and 3. The thread 14, in the illustrated case of Fig. 2 and Fig. 3, is knitted upon two needles only, and the thread passes from one needle to the next adjacent needle in each course and then back to the first needle for the next course, and so on, so long as the lap stripe is being formed. In Fig. 1 we have represented the lap stripes 5, 6 as interrupted at the heel 3 and all of the lap stripes as terminating at the toe 11. By suitable means (not herein disclosed) we may provide means for terminating the lap stripes, or any of them, at other points.

In Fig. 4, we have represented a hose 15 having a rib top 16, a heel 17, and a toe 18, said heel and toe being formed by narrowing and widening. In this instance, we have represented one lap stripe 19 which is a single needle in width, as most clearly shown in Fig. 5. Adjacent thereto is another lap stripe 20 separated therefrom by two wales, indicated generally at 21 in Fig. 5. Between the said lap stripes 19, 20, there are small spot-like areas 22 of normal plating and 23 of reverse plating, in alternation. Said spots of normal plating and reverse plating are shown upon a larger scale in Fig. 5. We have also shown a lap stripe 24 one needle in width, and adjacent thereto another lap stripe 25 a needle in width, and therebetween we have shown spot-like normal plating areas 26 and spot-like reverse plating areas 27. Between the lap stripe 20 and the lap stripe 24, which are relatively widely spaced, there are areas of normal plating (indicated generally at 28) and darker areas 29 of reverse plating. It will,

of course, be understood that the lap stripes 19, 20, 24 and 25 may, if desired, be more than a single wale in width. Where the lap stripes are relatively very close together, as, for example, in the embodiment of our invention shown in Fig. 5, a single additional thread 14 serves for both of the stripes, and the portion of said additional thread 14 between said two closely adjacent lap stripes is floated back and forth, as clearly indicated at 30 in Fig. 6, which is an inside view of the fabric.

It will, of course, be understood that the pattern effect of reverse plating may be widely varied within the scope of our invention. The particular means for introducing the two main yarns 12, 13 in a plating relation and for changing from a normal plating to a reverse plating relation will be hereinafter described.

It will be understood that the plating and reverse plating occur throughout the formation of the leg and the foot in the disclosed embodiment of the invention, and that the plating and reverse plating is suspended during the formation of the heel and the toe. During the formation of the heel and the toe, as already stated, the formation of the lap stripes is discontinued.

Referring to the pattern represented in Figs. 4 and 5, and to any one of the diamond shaped patterns shown in Fig. 6, it is to be understood that the upper block of four loops or stitches of each and every one of said diamonds is made in reverse plating through the action of the sinkers of a first group, and we have here marked the same 31. The two blocks next underneath are produced through the action of the sinkers of a second group and we have marked the same 32. The three blocks next underneath are produced through the action of the sinkers of a third group, and we have marked the same 33. The four blocks next underneath are produced through the action of the sinkers of a fourth group, and we have marked them 34. The three blocks next underneath are produced through the action of the sinkers of the third group and we have marked them 33. The two blocks next underneath are produced through the action of the sinkers of the second group, and we have marked them 32, and the single block terminating the diamond is produced through the action of the sinkers of the first group, and we have marked the same 31.

In this manner the series of diamonds between the widely separated lap stripes 20 and 24 are produced, and in a similar manner those blocks of reverse plating that are between closely adjacent lap strips are produced. Where, however, blocks or areas of reverse plating are made which are not in the same course as blocks of reverse plating in the diamonds, sinkers of still another group may be employed and certain of the blocks

produced thereby we have marked 35 in Fig. 4.

Obviously the diamond pattern is selected merely for illustration as the reverse patterning may be widely varied within the scope of our invention.

In Fig. 7, there are represented the circle of needles and the disk or plate 36 from which the exact position of said plates with respect to the needle circle is made clear.

In Figs. 8 and 9, we have represented the taking of an additional thread by one or more needles which are satisfactorily elevated for the purpose, and it will be observed in Fig. 8 that the two main threads indicated at A and B therein are introduced through thread guides A', B', so located that the needles which take the additional threads are restored to the level of the adjacent needles of the series, and that they take the two plating threads A and B. In Fig. 9, one of the needles is indicated at 38, and is shown in relation to the disk or plate 36 with its thread guides 37.

Having thus described one illustrative embodiment of our invention, and the best mode known to us for practicing the method of our invention and the fabric produced thereby, we desire it to be understood that although specific terms are employed, they are used in a generic and descriptive sense and not for purposes of limitation, the scope of the invention being set forth in the following claims.

Claims:

1. A knitted fabric composed of two main yarns which are knitted throughout entire courses including immediately succeeding courses in a plated relation, and one or more additional threads interknitted with said main yarns to form one or more superimposed lap stripes the said two main yarns existing in the completed fabric in such accurate plating relation and position in wales adjacent to, at each side of, said additional threads, that according to pattern requirements if and where desired for varied plating effects or areas in predetermined knitted loops, said two main yarns lie in response thereto in the completed fabric.

2. A knitted fabric composed of two main yarns knitted in a normal plated relation at portions thereof, and in a reversely plated relation at other portions thereof, and one or more additional threads interknitted as a lap stripe or stripes in superposed relation to said normally plated portions of the said fabric.

3. A knitted fabric consisting of two main yarns knitted in part in a normal plated relation and in part in a yarn variation of normal plating, and one or more additional threads interknitted in superposed relation with portions of said fabric that are in normal plating.

4. A seamless or tubular knitted fabric consisting of two yarns knitted in part in a plated relation, and knitted in part in a reversely plated relation, and one or 5 more lap stripes consisting each of an additional thread knitted in a direction lengthwise of the fabric into only portions thereof of having the two main yarns in a normal plated relation.
- 10 5. A seamless hose or stocking, the main portion whereof is composed of two main yarns which are knitted throughout entire courses including immediately succeeding courses in a normal plating relation, and one or more additional threads interknitted as lap stripes onto said plated threads, the said two main yarns existing in the completed fabric in such accurate plating relation and position in wales adjacent to, at each side of, said 15 additional threads, that according to pattern requirements if and where desired for varied plating effects or areas in predetermined knitted loops, said two main yarns lie in response thereto in the completed fabric.
- 20 6. A knitted fabric composed of two main yarns knitted in a normal plated relation in part, and knitted in a reversely plated relation in the remaining part, and having a plurality of additional threads interknitted with 25 said main yarns to form a plurality of lengthwise extending stripes, certain of said stripes being close together and the two main yarns between said close stripes being knitted in part in a normally plated relation and in 30 part in a reversely plated relation.
- 35 7. A knitted fabric composed of two main yarns knitted in a normal plated relation in part and knitted in a reversely plated relation in the remaining part, and having a plurality of additional threads interknitted with 40 said main yarns to form a plurality of lengthwise extending stripes, certain of said stripes being close together and the two main yarns between said close stripes being knitted in part in a normally plated relation and in 45 part in a reversely plated relation, the additional thread of which said close lap stripes is composed being floated between said stripes at the back of the fabric.
- 50 8. That method of knitting a fabric comprising knitting two main yarns throughout entire courses including immediately succeeding courses, in a plating relation and interknitting an additional thread into loops of 55 the said plated yarns, thereby forming a lap stripe upon the surface of the plated knitted fabric and during the knitting operation, maintaining the two main yarns in such accurate plating control and relation in wales adjacent to, at each side of, said lap threads, that if or where pattern requirements are 60 for reverse plating effects or areas in predetermined loops, the said two main yarns respond in the knitting operation to such requirements by reversal at such loops so as at such loops to lie in reverse position.
- 65 9. That method of knitting a fabric comprising knitting two main yarns in part in a normal plated relation and in part in a reversely plated relation, and interknitting with normally plated loops an additional thread or threads, thereby forming a lap stripe or stripes upon normally plated portions of the said fabric.
- 70 10. That method of knitting a fabric which consists in knitting two main yarns throughout entire courses including immediately succeeding courses, in a normal plating relation, effecting yarn variation at portions of said 75 fabric, and interknitting an additional thread or threads as lap stripes into normally plated loops of the fabric.
- 80 11. That method of knitting a seamless fabric comprising knitting two main yarns in a normal plating relation, and upon portions of said normally plated yarns interknitting an additional thread to make a lap stripe, and at other portions of said fabric varying the yarn relation of the said two 85 main yarns to cause the backing yarn of the normally plated portion of the fabric to appear at the face.
- 90 12. That method of knitting a seamless or tubular stocking comprising knitting two 95 yarns throughout entire courses, including immediately succeeding courses, in a normal plating relation and interknitting therewith at one or more points an additional thread as a lap stripe whereby the two main yarns and 100 each additional thread are received by selected needles and cast off together and during the knitting operation, maintaining the two main yarns in such accurate plating relation and control in wales adjacent to, at each side of, said additional threads, that wherever pattern requirements are for reversed plating effects or areas in predetermined loops, the said two main yarns respond in knitting 105 to such requirements by reversal at such loops thereby lying in the completed fabric in reverse position at such loops.
- 110 13. A knitted fabric composed of two main 115 yarns and a plurality of subsidiary yarns, the two main yarns appearing in a plated relation at all the loops of the fabric, and the subsidiary yarns respectively appearing in superposed relation at the outer face of the 120 fabric at certain of the loops only, the said two main yarns existing in the completed fabric in such accurate plating relation and position in the wale or wales underneath the subsidiary yarns and in wales adjacent to, at each side of, said subsidiary yarns, that according 125 to pattern requirements if and where desired for varied plating effects or areas in predetermined knitted loops, said two main yarns lie in response thereto in the completed fabric.
14. A knitted fabric composed of two main 130 yarns and a plurality of subsidiary yarns,

- the two main yarns appearing in a plated relation at all the loops of the fabric, and the subsidiary yarns respectively appearing in superposed relation at certain of the loops 5 only at the inner face of the fabric, the said two main yarns appearing in a normal plated relation at portions of the fabric and in a reverse plated relation at other portions of the fabric.
- 10 15. A hose or stocking having the leg and foot thereof composed of two body yarns which are knitted throughout entire courses, including immediately succeeding course, in a plating relation and having at the opposite 15 sides thereof at substantially the clocking areas a third yarn knitted in with the loops of the said two body yarns, so as to appear on the outer face of the said hose or stocking and contrasting with the said body yarns, where- 20 by at substantially said clocking areas three yarns exist in each of the loops, the said two body yarns existing in the completed fabric in such accurate plating relation and position at the clocking areas and in wales ad- 25 jacent to, at each side of said clocking areas, that according to pattern requirements if and where desired plating effects or areas in pre- determined knitted loops, said two main areas lie in response thereto in the completed fab- 30 ric.
16. A hose or stocking having the leg and foot thereof composed of two body yarns which are knitted throughout entire courses, including immediately succeeding course, in a plating relation and having at intervals a third yarn knitted in with the loops of the said two body yarns, so as to appear at said intervals on the outer face of the said hose or stocking, and there contrasting with the 35 said body yarns, whereby at said intervals three yarns exist in each of the loops, the said two body yarns existing in the completed fabric in such accurate plating relation and position where the third yarn is knitted in 40 and also in wales adjacent to the knitting in of said third yarn, that according to pattern requirements if and where desired for varied plating effects or areas in predetermined knitted loops, said two main yarns lie in response 45 thereto in the completed fabric.
17. A hose or stocking having the leg and foot thereof knitted throughout of two body yarns in a plating relation, so that one yarn appears at the inner face of the stocking and 50 the other yarn appears at the outer face of the stocking, but with said two body yarns re- versed in position at intervals, said hose or stocking having at intervals a third yarn knitted in with the loops of the said two body 55 yarns, so as to appear at said intervals on the outer face of the said hose or stocking and there contrasting with the said body yarns, whereby at said intervals the yarns exist in each of the loops.
- 60 65 18. A knitted fabric composed of two main
- yarns and a plurality of subsidiary yarns, the two main yarns appearing in a plated relation at all the loops of the fabric, being in a normal plating relation at certain of the loops and in a reverse plated relation at all the 70 other loops, the series of subsidiary yarns appearing in superposed relation at the outer face of the fabric at normal plated portions only thereof and not impairing or interrupting the normal plated relation of the two 75 main yarns upon which are superposed the said subsidiary yarns.
19. That method of knitting a fabric comprising knitting two main yarns in a plated relation throughout but in normal plated relation at predetermined areas and in re- versely plated relation at the remaining areas, and while maintaining plating control of said two main yarns at the normal plated areas, superimposing upon the outer face of 80 the fabric at certain normally plated areas an additional yarn or yarns whereby a lap stripe or stripes upon desired normally plated areas is or are superimposed upon de- sired normally plated portions of the fabric 85 without interrupting or impairing the normal plating positions of the said two main yarns.
20. A knitted fabric composed of two main yarns knitted in a normal plated relation at portions thereof and in a reversely plated 90 relation at other portions thereof, and one or more additional threads each superimposed upon normally plated areas along two lines closely adjacent each other, each such additional thread being floated at the back of 95 the fabric from one of said lines to the other.
21. That method of knitting a fabric comprising knitting two main yarns in a plating relation throughout but in a normal plated relation at parts only of the fabric and in a reverse plated relation at the remaining parts of the fabric, and interknitting in a super- posed relation on the outer face of the fabric an additional yarn along two closely ad- 100 jacent but spaced lines at normal plated por- tions of the fabric, and floating said addi- tional yarn from one of said lines to the other 105 at the inner face of the fabric without dis- turbing the normal plating relation of the 110 said two main yarns.

CERTIFICATE OF CORRECTION.

Patent No. 1,848,362.

Granted March 8, 1932, to

JOHN LAWSON ET AL.

It is hereby certified that error appears in the printed specification of the above numbered patent requiring correction as follows: Page 5, line 27, claim 15, after the word "desired" insert the words for varied; and that the said Letters Patent should be read with this correction therein that the same may conform to the record of the case in the Patent Office.

Signed and sealed this 26th day of April, A. D. 1932.

**M. J. Moore,
Acting Commissioner of Patents.**
